UNITED STATES PATENT OFFICE

158,694

WRIST WATCH

Bruno Santini, Lausanne, Switzerland

Application September 2, 1949, Serial No. 4,842
In Switzerland May 21, 1949

Term of patent 3½ years

(Cl. D42—8)

To all whom it may concern:

Be it known that I, Bruno Santini, a citizen of Italy, and residing at rue Etraz 11, Lausanne, Switzerland, have invented a new, original, and ornamental Design for a Wrist Watch, of which the following is a specification, reference being made to the accompanying drawing, forming part thereof.

Fig. 1 is a front view of the wrist watch, showing my new design;

Fig. 2 is a side elevational view of the wrist watch of Fig. 1;

The rear of the wrist watch is substantially plain and flat and the parts shown in broken lines in Fig. 1 being merely representative of that which might appear there.

I claim:

The ornamental design for a wrist watch, substantially as shown and described.

BRUNO SANTINI.
